ATTEST.

UNITED STATES PATENT OFFICE.

LAURITZ W. ANDERSEN, OF WATERBURY, CONNECTICUT.

UPRIGHT SHADE-HOLDER.

1,235,632.

Specification of Letters Patent.

Patented Aug. 7, 1917.

Application filed October 28, 1915. Serial No. 58,382.

To all whom it may concern:

Be it known that I, LAURITZ W. ANDERSEN, a citizen of the United States, residing at Waterbury, in the county of New Haven and

5 State of Connecticut, have invented a certain new and useful Improvement in Upright Shade-Holders, of which the following is a full, clear, and exact description, reference being had to the accompanying drawings.

This invention relates to a shade holder for electric lighting devices and more particularly to a combined socket holder and shade support.

15 The object of the invention is to provide a simple and inexpensive socket support capable of maintaining the socket and lamp in an upright position, said socket holder serving also to support the shade holding 20 and supporting means.

Another object of the invention is to provide a combination device embodying these characteristics which will avoid the use of screws for holding both the socket and the 25 shade.

With these objects in view the invention consists in the novel features of construction hereinafter fully described and pointed out in the claims.

30 In the drawings forming a part of this specification Figure 1 is a view partly in section and partly in elevation showing the practical application of my invention. Figs. 2, 3 and 4 are detail views illustrating 35 the means for securing the socket in its holder. Fig. 5 is a sectional view of a modified form of shade securing means.

Referring to the drawings A indicates a socket of the usual or well known construction to which is connected the usual incandescent lamp B. The socket A is inserted and secured in a holder C which is in the form of a sleeve open at both ends, the inner or upper end being slightly contracted, 45 said contracted portion being formed with an annular groove D which is adapted to receive the bead E of the socket A, and this contracted end of the sleeve is slit vertically as shown at F, the inner portions of said 50 slits being enlarged as shown at F' in order to increase the resiliency of the upper end portion of the sleeve. The extreme end of the sleeve is formed with an outwardly projecting annular flange G which is adapted 55 to coöperate with a clamping ring H which is attached to the sleeve C. The

lower end of the clamping ring being screw-threaded as shown at I and adapted to engage the screw-threaded portion K of the sleeve I, this threaded portion I being 60 just below the slotted portion of the sleeve as most clearly shown.

The bottom of the sleeve can be slotted to receive a key or pull socket.

The socket A is inserted in the sleeve from 65 the bottom, and after being properly positioned, the clamping ring is placed over the split end of the sleeve and is screwed securely upon said sleeve and in such operation this clamping ring will engage the 70 flanged and grooved portions of the split end of sleeve and bind the same securely against the socket, thereby firmly holding the socket within the holder.

Attached to the holder C are the arms L 75 curved as shown to provide ample space for the incandescent lamp, and at their upper ends these arms are attached to a flanged disk M, the shade N, being adapted to fit upon this flanged disk and be secured in 80 place by means of a cup or cap O, centrally apertured to receive the bolt P which screws into a nut Q at the center of the disk O thereby clamping the shade between the disk and cap. 85

In Fig. 5 is shown a slight modification of shade clamp, the disk N carrying a threaded post R, which passes through the cap O and receives a nut or knob S. The socket holder therefore affords ample provision for the 90 shade support and also the means for securely fastening the socket within the holder.

While I have shown this combined socket holder and shade support as upright, it is 95 obvious that it can be employed in the reverse position if so desired.

Having thus described my invention, what I claim is:

1. In a device of the kind described, a 100 socket receiving member having a rigid and a resilient portion, said rigid portion being adapted to receive the body of a socket and the resilient portion adapted to engage the lamp receiving end thereof, a clamping ring 105 adapted to engage said resilient portion and shade supporting arms extending from the rigid portion of the socket receiving member.

2. In a device of the kind described, a socket receiving member having a rigid portion adapted to receive the body of a socket, and a resilient portion adapted to engage 110

the end of the socket, said rigid portion having a key slot, a clamping ring adapted to engage the resilient portion of socket receiving member, and shade supporting arms 5 attached to the rigid portion and extending beyond the resilient portion, as set forth.

In testimony whereof, I hereunto affix

my signature in the presence of two witnesses.

LAURITZ W. ANDERSEN.

Witnesses:

E. A. GODFREY,
E. W. ANDERSEN.
